(57) **CLAIM**

The ornamental design for fishing lure with contrasting features, as shown and described.

DESCRIPTION

FIG. 1 is a perspective view of a first embodiment of a fishing lure with contrasting features showing my new design, the broken lines being for illustrative purposes only and forming no part of the claimed design;
FIG. 2 is a front view, with the rear view being a mirror image thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view of a second embodiment of a fishing lure with contrasting features, the broken lines showing the eye portion being for illustrative purposes only and forming no part of this embodiment;
FIG. 8 is a front view, with the rear view being a mirror image thereof;

FIG. 9 is a top plan view thereof;

FIG. 10 is a bottom plan view thereof;

FIG. 11 is a left side view thereof; and,

FIG. 12 is a right side view thereof.
